UNITED STATES PATENT OFFICE.

JAMES FRANCIS ROWLEY, OF CHICAGO, ILLINOIS.

ARTIFICIAL LIMB.

1,258,710.

Specification of Letters Patent. Patented Mar. 12, 1918.

Application filed June 18, 1917. Serial No. 175,385.

To all whom it may concern:

Be it known that I, JAMES F. ROWLEY, a citizen of the United States of America, and a resident of Chicago, county of Cook, and 5 State of Illinois, have invented certain new and useful Improvements in Artificial Limbs, of which the following is a specification.

The main objects of this invention are to provide an improved form of back check for 10 artificial limbs of the general type shown in my Patent No. 644,464, dated February 27, 1900; and to provide an improved form of swingable connection between the back check and suspender, whereby the back check and 15 suspender may move relatively to each other during certain movements of the limb or the wearer's body, without causing the suspender to be shifted on the shoulder of the wearer.

20 An illustrative embodiment of the invention is shown in the accompanying drawings, in which—

Figure 1 is a sectional elevation of a portion of an artificial limb showing the improved back check and swingable suspender connection.

Fig. 2 is a fragmentary detail in side elevation, showing the different positions which the swingable suspender connection 30 may assume.

Fig. 3 is a back elevation of the upper end of the back check and swingable suspender connection.

In the construction shown in the drawings, the artificial limb comprises a shin section 1 pivotally connected to a thigh section 2 by a knee-bolt 3.

The back check is mounted on the shin section 1 and comprises a body part 4, a base 40 part 5 adapted to be rigidly attached to the shin section 1 by bolts 6, an upper end 7 adapted to bear against the knee-bolt 3, and a forwardly projecting arm 8 on said upper end, the form of back check shown, having 45 the open sided seat and the arm 8 extending at an angle to the body portion of the back check is in effect a bell crank lever, the leverage of which may be slightly altered to exactly suit the user of the device by employing pads 11 of different thicknesses. Accordingly the pivotal connection 14 between arm 8 and link 12 may be shifted with respect to the pivotal center provided by the knee-bolt 3.

55 The thigh section 2 is provided with a slot 9 at the lower rear side thereof, through

which the upper part of the back check extends, and the lower end of said slot has a pad or cushion 10 therein against which the back check is adapted to contact, so as to 60 limit the relative pivotal movement of the limb sections. When the limb sections are straightened to the position shown in Fig. 1, the pad 10 bears against the body part 4 of the back check and the upper end 7 of 65 the back check bears against the knee-bolt 3, thus providing a stop of great strength to prevent further movement. A pad of leather or other suitable material 11 is interposed between the knee-bolt 3 and the back check. 70

The outer end of the forwardly projecting part 8 of the back check has a link swingably mounted thereon, which comprises a pair of side plates 12 and 13 pivotally mounted at their lower ends by a pin 14 on 75 the outer end of the forwardly projecting part 8. The upper ends of the side plates 12 and 13 have a pin 15 passing therethrough upon which is journaled a pair of rollers 16, which coact with the loops 17 of the suspender. 80

In the operation of the device, the two loops of the artificial limb suspender which pass down one on each side of the artificial limb pass through suitable apertures in the 85 thigh section 2 and around the rollers 16. When the thigh section is projected forwardly to take a step, the swingable link connection between the forwardly projecting part 8 of the back check and the suspender 90 permits considerable movement between the suspender and back check without causing the rollers to run along the cords and thereby slipping the suspender forwardly or backwardly on the shoulder of the wearer. 95

When the thigh section is lifted forwardly, the shin section rotates rearwardly on the knee-bolt 3, and the back check works in the slot 9 of the thigh section 2. When the sections are again straightened through 100 the action of the suspender as described in my said patent, and pressure is brought to bear on the artificial limb as in taking a step forward thereon, the back check contacts with the pad or cushion 10 and limits 105 the pivotal movement. When the pad 10 contacts with the back check, the upper end 7 bears against the knee-bolt 3 and serves as a support therefor, thus avoiding undue strain on the bolts at the base part 5. 110

Although but one specific embodiment of this invention has been herein shown and

described, it will be understood that numerous details of the construction shown may be altered or omitted without departing from the spirit of this invention as defined by the following claims.

I claim:

1. In an artificial limb, the combination of leg and thigh sections pivotally connected at the knee, an operating member fixed to the leg section and extending upwardly into the thigh section to a point located in front of said pivotal connection, said operating member bearing at one side only against said pivotal connection, and a link swingably

mounted on said operating member and 15 adapted to coact with a suspender.

2. In an artificial limb, the combination of leg and thigh sections pivotally connected by a knee-bolt, a back check secured to the leg section and extending upwardly into the 20 thigh section in front of said knee-bolt and having an open-sided seat bearing on said knee-bolt, and means attached to said back check in front of said knee-bolt adapted to coact with a suspender.

Signed at Chicago this 14th day of June 1917.

JAMES FRANCIS ROWLEY.
